UNITED STATES PATENT OFFICE.

WILLIAM M. MITCHELL, OF LOUISVILLE, KENTUCKY.

RAIL-ANCHOR.

1,333,270.

Specification of Letters Patent.

Patented Mar. 9, 1920.

Application filed December 22, 1919. Serial No. 346,680.

To all whom it may concern:

Be it known that I, WILLIAM M. MITCHELL, a citizen of the United States, and a resident of Louisville, in the county 5 of Jefferson and State of Kentucky, have invented certain new and useful Improvements in Rail-Anchors, of which I do declare the following to be a full, clear, and exact description, reference being had to the 10 accompanying drawing, forming a part of this specification.

The invention consists in the features of novelty hereinafter described, illustrated in the accompanying drawing and particularly 15 pointed out in the claims at the end of this specification.

Figure 1 is a plan view of my improved anchor as applied to the base flange of a railway rail, the web of the rail being shown 20 in horizontal section and a portion of a cross tie being also shown. Fig. 2 is a plan view of the lower portion of the rail with the anchor removed. Fig. 3 is a detail view in 25 vertical section on line 3—3 of Fig. 2. Fig. 4 is a view in end elevation of the anchor shown in Fig. 1 and in the position as it is about to be applied to the rail, which is shown in vertical section. Fig. 5 is a view 30 of the parts illustrated in Fig. 4 but showing the anchor in position for use. Fig. 6 is a plan view similar to Fig. 1 but showing a slight modification of the anchor. Fig. 7 is a view similar to Fig. 4 but showing a 35 modified manner of applying the anchor. Figs. 8 and 9 are views similar to Figs. 1 and 2 but showing a modified form of the anchor. Fig. 10 is a view in vertical section on line 40 10—10 of Fig. 9. Figs. 11 and 12 are views similar to Figs. 4 and 5 but showing modifications of the anchor and of the stops on the base flange of the rail. Fig. 13 is a view similar to Fig. 8 but showing a modification 45 of the parts.

Referring to the accompanying drawings, 45 A designates the railway rail, to one of the flanges α of which my improved anchor will be applied; and B denotes the cross tie on which the rail A will rest. In the preferred 50 form of my invention, my improved anchor is made from a single piece of metal and its upper portion comprises a jaw adapted to engage the base flange of the rail, while

its lower portion comprises an abutment adapted to engage with the cross tie B whereon the rail rests. The jaw of the 55 anchor is formed with the upper member c adapted to extend over the base flange α of the rail and with a lower member c' that extends beneath and engages the bottom surface of the base flange of the 60 rail. From the inner edge of the lower member c' of the anchor jaw depends a member c^2 with which is connected an abutment member c^3 that extends at right angles to the member c^2 and is adapted to bear against 65 the face of the tie B. My improved anchor is preferably made from a sheet of metal cut to form L-shaped blanks, from which blanks anchors will be shaped by suitable dies.

The upper member of my improved 70 anchor is adapted to engage with one or more stops a^2 on the upper surface of the base flange α of the rail and preferably, to enable the upper member of the anchor to engage a stop on the base flange of the rail; 75 the member c of the anchor is formed with one or more openings or cut away spaces c^4 so that when the anchor is in position for use, the inner end portion of the anchor will engage with the stop on the rail base flange 80 and hold the anchor in secure engagement therewith. The stops a^2 are preferably formed upon the outer surface of the base flange of the rail by welding onto the rail small portions of metal and this manner of 85 forming the stops can be readily effected by the familiar welding processes now in common use, such for example, as the oxy-acetylene process. Preferably, the stop or stops a^2 on the base flange of the rail have 90 their upper surfaces downwardly and outwardly inclined, as at a^3 , and preferably, also, the lower portion of the inner edge of the member c of the anchor jaw is inclined or beveled, as at c^5 , to enable the anchor to 95 be more readily driven onto the base flange of the rail and to such position that the upper member c of the jaw shall interlock with the stop or stops a^2 . The upper member of the jaw is flexible and preferably resiliant so that the anchor can be caused to 100 engage with the stop or stops on the rail base flange.

The preferred manner of applying my

improved anchor to the rail base flange is illustrated in Fig. 4 of the drawings; that is to say, the jaw of the anchor is slipped partially over the base flange a of the rail 5 until the inner edge of the member c engages with the stop or stops a^2 of the rail base flange. Then, by means of a hammer, the anchor will be forced farther over the base flange a until the hole or cut away space in 10 the upper member c of the anchor is above the stop or stops a^2 , when the resiliency of the jaw member c will cause this member to snap into engagement with the stop or stops a^2 . 15 If desired, my improved anchor may be applied to the rail base flange in the manner illustrated in Fig. 7 of the drawings. That is to say, the upper jaw member c , at the time the anchor is slipped into engagement with the rail base flange, may stand at such angle with respect to the lower jaw member c' that the upper jaw member will pass over the stop a^2 on the base flange a , after which, by means of a suitable tool, the upper jaw member c will be forced downwardly so that the stop a^2 shall enter the opening or cut away space c^4 of the upper jaw member. When this manner of applying the anchor is adopted, the 20 inner edge of the jaw member c need not be beveled. 25 When the upper jaw member c is formed with a plurality of holes or cut away spaces to engage a plurality of stops on the rail base flange, these holes or cut away spaces will be arranged at opposite sides of the center of the anchor and adjacent the ends of the upper jaw member c ; but if desired, the upper jaw member may be formed with 30 a single hole or cut away space to receive a stop formed upon the base flange of the rail, this construction being illustrated in Fig. 6 of the drawing. In Fig. 6, the upper member c of the anchor is formed with 35 a single long hole or slot c^4 and a single long stop a^2 will be formed upon the upper surface of the base flange a of the rail A.

In the forms of my invention illustrated in Figs. 8 to 12 of the drawings, the base flange a of the rail has stops a^2 of somewhat different shape, these stops being provided at their ends with extensions a^5 forming a recess between them to receive the downwardly projecting part or shoulder c^6 formed at the inner end of the member c of the rail anchor. This downwardly projecting part c^6 is preferably formed by depressing the inner edge of the member c , which can readily be done by the dies used 60 in forming the anchor. The inner edge of each of the parts c^6 is preferably beveled or inclined to ride over the inclined surfaces of the corresponding stops a^2 . By reference to Fig. 11, it will be seen how the anchor 65 is initially applied to the base flange of

the rail A, after which it will be forced inward until it completely engages with the stops a^2 , as shown in Fig. 12.

In Fig. 13, the construction of anchor shown is similar to that illustrated in Figs. 8 to 12, except that the upper member c of the anchor jaw is formed centrally with a single depressed part or shoulder c^6 and the base flange of the rail is formed with a single stop corresponding to the stop 75 shown in Fig. 9 of the drawing.

Having thus described my invention, what I claim as new and desire to secure by Letters Patent is:—

1. A rail anchor comprising a jaw to engage the base flange of a rail and a part to engage a cross tie, the upper member of said jaw being flexible and being provided with means to engage a stop on the rail. 80

2. A rail anchor comprising a jaw to engage the base flange of a rail and a depending abutment to engage a cross tie, the upper member of said jaw being flexible and resilient and being provided with means to engage a stop on the rail. 85

3. A rail anchor comprising a jaw adapted to engage the base flange of a rail and provided adjacent its opposite ends with means to engage stops on the base flange of the rail. 90

4. A rail anchor comprising a jaw to engage the base flange of a rail and with a part to engage a cross tie, the upper member of said jaw being provided with means to engage a stop on the rail base flange and having its inner edge beveled to ride over said stop. 100

5. A rail anchor comprising a jaw to engage the base flange of a rail, and a part to engage a cross tie, and having a downwardly projecting part to engage a stop on the base flange of the rail. 105

6. A rail anchor comprising a jaw to engage the base flange of a rail, and a part to engage a cross tie, and having a downwardly projecting part to engage a stop on the base flange of the rail, said last mentioned part being formed by depressing a part of the upper member of the anchor jaw. 110

7. The combination with a rail having a stop thereon, of a rail anchor comprising a jaw to grip the base flange of said rail, the upper member of said jaw being flexible and being provided with means to engage said stop. 115

8. The combination of a rail having the upper surface of its base flange provided with a stop welded thereon, and an anchor having a jaw to grip the base flange of said rail, said anchor being provided with means to engage said stop. 120

9. The combination with a rail having a stop thereon, of a rail anchor comprising a jaw to grip the base flange of said rail, the 125

130

upper member of said jaw being provided with a downwardly projecting part or shoulder and the upper face of the rail base flange being provided with means to engage 5 said part or shoulder to hold the anchor in position upon the rail.

10. The combination of a rail having its

base flange provided with a stop formed with side and end walls, and a rail anchor comprising a jaw adapted to grip the base 10 flange of the rail, the upper member of said jaw having a depending part adapted to engage with said stop.

WILLIAM M. MITCHELL.
